CLAIM

The ornamental design for a cash box, as shown and described.

DESCRIPTION

FIG. 1 is a front, right, and top exploded perspective view of a cash box, showing my new design;
FIG. 2 is a rear, left and bottom exploded perspective view of FIG. 1;

FIG. 3 is a front exploded view thereof;

FIG. 4 is a rear exploded view thereof;

FIG. 5 is a left side exploded view thereof;

FIG. 6 is a right side exploded view thereof;

FIG. 7 is a top exploded view thereof;

FIG. 8 is a bottom exploded view thereof;

FIG. 9 is an enlarged portion view labeled "9," in FIG. 1;
FIG. 10 is a front, right, top perspective view of the cash box shown in a closed configuration;

FIG. 11 is a rear, left and bottom perspective view of the cash box shown in a closed configuration; and,

FIG. 12 is another front, right, top perspective view of the cash box shown in an open configuration with the top lid of the tray closed.

The broken lines depict portions of the cash box that form no part of the claimed design. The dot-dash broken lines in FIGS. 1 and 9 depict the boundaries of the enlargements that form no part of the claimed design.

1 Claim, 12 Drawing Sheets
